UNITED STATES PATENT OFFICE

108,625

DESIGN FOR A FLOWER BASKET

Roderic M. Koch, Evansville, Ind.

Application December 16, 1937, Serial No. 73,664

Term of patent 7 years

To all whom it may concern:

Be it known that I, Roderic M. Koch, a citizen of the United States of America, residing at Evansville, in the county of Vanderburg and State of Indiana, have invented a new, original, and ornamental Design for Flower Baskets, of which the following is a specification, reference being had to the accompanying drawing, forming part thereof.

turned through an angle of ninety degrees from the position of Figure 1.

Figure 4 is a horizontal transverse sectional view, as at line 4—4 of Figure 2, also omitting the can in order that the appearance of parts may more readily be illustrated.

I claim:

The ornamental design for a flower basket, as shown.

RODERIC M. KOCH.
